UNITED STATES PATENT OFFICE.

ROBERT NORDENSWAN, OF NEW YORK, N. Y., AND RICHARD C. WINCKEL, OF ELIZABETH, NEW JERSEY, ASSIGNEES TO WESTERN ELECTRIC COMPANY, INCORPORATED, OF NEW YORK, N. Y., A CORPORATION OF NEW YORK.

TELEPHONE-RECEIVER.

1,330,214.

Specification of Letters Patent. Patented Feb. 10, 1920.

Application filed January 4, 1918. Serial No. 210,341.

To all whom it may concern:

Be it known that we, ROBERT NORDENSWAN, a subject of the King of Sweden, and RICHARD C. WINCKEL, a citizen of the United States, residing at New York, in the county of New York and State of New York, and at Elizabeth, in the county of Union and State of New Jersey, respectively, have invented certain new and useful Improvements in Telephone-receivers, of which the following is a full, clear, concise, and exact description.

This invention relates to telephone receivers and more particularly to the magnet systems thereof.

An object of this invention is to provide a magnet system of increased efficiency for a telephone receiver by employing a pole-piece material having a high permeability, which pole-piece is intimately united to the rest of the magnet system by a highly efficient and low reluctance joint.

Due to its high maximum permeability and its sharply defined permeability curve, which falls off rapidly beyond the point of maximum permeability, it has been found that silicon steel is desirable for use in telephone receiver pole-pieces. It is, however, extremely difficult owing to the physical characteristics of such material to join it to the tungsten or other magnet steel used for the permanent magnet by a joint having very low reluctance.

In accordance with one feature of this invention, an intermediate member composed of soft iron is securely clamped to and intimately associated with a silicon steel pole-piece by an embossing process and such soft iron member is welded to the adjacent end of the permanent magnet.

These and other features of the invention will more clearly appear from the following specification and annexed drawing showing a receiver illustrating the preferred embodiment of the invention and the parts entering into such a structure.

Figure 1 is a sectional view of the receiver with the magnet system partially in section and with one magnet coil omitted; Fig. 2 is an end view with the cap, a portion of the diaphragm and one magnet coil omitted; Fig. 3 is a fragmentary perspective view before assembly of one pole-piece attached to its associated intermediate mem-

ber together with portions of the cup and of the permanent magnet; Fig. 4 is a perspective view of one pole-piece and its associated intermediate member assembled; and Fig. 5 is a sectional view of the pole-piece and its intermediate member, along the line 5, 5 of Fig. 4.

Referring to the drawings, 1 is a permanent magnet of tungsten or other magnet steel, each end of which is electrically welded to the projecting portion 4 of a soft iron intermediate or supplemental member 2. Projecting portions 15, of member 2, are formed or bent around the silicon steel pole-piece 3 and are further secured thereto by embossed portions 6, which engage corresponding apertures 8 in the pole-piece 3. The inclosing cup 9 of non-magnetic material is provided with slots or perforations 10 through which the portions 4 extend, which portions are welded to the ends of the permanent magnet 1. The cup is clamped in position between the ends of the permanent magnet 1 and the adjacent ends of the pole-pieces 3, in co-operation with the extending portions 15 of the members 2. The pole-piece 3 is provided with the usual shoulders 7, serving as a stop for the magnet coil 11. In the ordinary manner, diaphragm 12 rests upon the flange of the cup 9 and is clamped in position by means of the ear cap 13 co-operating with the casting 14.

In practice the pole-piece 3 is placed within the intermediate member 2, the projections 15 are formed around the pole-piece, and at points 6, are caused to engage the apertures 8 of the pole-piece 3 by a staking or an embossing process. The resultant unitary structure, as shown in Figs. 4 and 5, is then placed in position with the portion 4 of the intermediate member 2 extending through the slot 10 of the cup 9 and the adjacent end of the permanent magnet is electrically welded thereto.

What is claimed is:

1. A magnet system for telephone receivers comprising a permanent magnet, a pole-piece and an intermediate member secured to said permanent magnet having a portion embracing and clamping said pole-piece.

2. A magnet system for telephone receivers comprising a permanent magnet, a pole-piece having an aperture therein, and an in-

termediate member secured to said permanent magnet and having a portion thereof forced into such aperture for securing said member to said pole-piece.

5. A magnet system for telephone receivers comprising a permanent magnet, a pole-piece having an aperture therein, and an intermediate member secured to said permanent magnet, having a portion embracing and clamping said pole-piece and engaging such aperture.

10. A magnet system for telephone receivers comprising a permanent magnet, a pole-piece and intermediate member secured to said permanent magnet having a portion embracing and clamping the pole-piece and a cup surrounding the pole-piece, and secured in position by the coöperation of said permanent magnet, said pole-piece and said intermediate member.

15. A magnet system for telephone receivers comprising a permanent magnet, a cup having a slot therein and resting against the end of the magnet, a pole-piece and an intermediate member having a portion passing through the slot and secured to the permanent magnet and having another portion embracing and clamping said pole-piece and coöoperating with the magnet to clamp said

20. cup in position.

30. 6. A magnet system for telephone receivers comprising a permanent magnet, a cup

having a slot therein, a pole-piece having a plurality of apertures therein, an intermediate member having one portion thereof 35 passing through the slot and welded to the permanent magnet, and having another portion embracing and clamping said pole-piece engaging the apertures therein and coöperating therewith, and with the permanent 40 magnet to clamp said cup in position.

7. A magnet system for telephone receivers comprising a permanent magnet, a pole piece and a member of magnetic material interposed between said magnet and said pole 45 piece, said member being secured to said permanent magnet and having portions embracing and clamping said pole piece.

8. A magnet system for telephone receivers comprising a permanent magnet, a pole 50 piece and a member of magnetic material interposed between said permanent magnet and said pole piece, said member being secured to said permanent magnet and having a portion embracing and clamping said pole 55 piece, and a cup surrounding said pole piece and secured in position by the coöperation of said permanent magnet, said pole piece and said member.

In witness whereof we hereunto subscribe 60 our names this 28th day of December, A. D. 1917.

ROBERT NORDENSWAN.
RICHARD C. WINCKEL.
